(57) **CLAIM**

The ornamental design for a digit separator, as shown and described.

DESCRIPTION

FIG. 1 illustrates a front perspective view of a digit separator employing an ornamental design in accordance with the present invention;

FIG. 2 illustrates a front plan view of the digit separator of FIG. 1, the back plan view being a mirror image thereof;

FIG. 3 is a left side plan view of the digit separator of FIG. 1, the right side plan view being a mirror image thereof;

FIG. 4 is a top plan view of the digit separator of FIG. 1, the bottom plan view being a mirror image thereof;

FIG. 5 illustrates a front perspective view of a second modified embodiment of a digit separator employing an ornamental design in accordance with the present invention;

FIG. 6 illustrates a front plan view of the digit separator of FIG. 5, the back plan view being a mirror image thereof;

FIG. 7 is a bottom plan view of the digit separator of FIG. 5;

FIG. 8 is a top plan view of the digit separator of FIG. 5; and,

FIG. 9 is a left side plan view of the digit separator of FIG. 5, the right side plan view being a mirror image thereof.
